UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

INTERLOCKING MECHANISM.

Application filed December 5, 1925. Serial No. 73,525.

This invention relates to interlocking mechanisms and more particularly to interlocking controlling mechanisms especially adapted to use in conjunction with the 5 trollers and current supply connections of mining machines.

The present day coal cutting mining machine of the electrically operated type is commonly provided with a suitable 10 controller and is supplied with current through a suitable detachable connection. The controller is ordinarily of the rotatable type and upon rotation in opposite directions from a neutral position is adapted to effect the 15 proper starting and running in opposite directions of the mining machine motor. The connector plug is ordinarily of the longitudinally insertable type and contains a number of push connections for making the 20 necessary circuits and also generally a ground connection.

It is an object of the present invention to provide an improved interlocking controlling mechanism for effecting the operation 25 of a controller of the type specified and locking the connector plug against removal or insertion as this may be necessary, as for example in all cases except when the controller is in "off" position. A more specific 30 object of the invention is to provide an improved interlocking connection including manually controllable means determining the direction of operation of the motor controller and operating to lock or release a 35 detachable connector plug. Other objects and advantages of the invention will subsequently appear.

In the accompanying drawings in which one illustrative embodiment of the invention 40 is shown:

Fig. 1 is a plan view with parts broken away to different degrees of the extreme rear end of a mining machine equipped with the 45 illustrative embodiment of the invention.

Fig. 2 is a rear end elevation of the upper portion of the controller end of such a mining machine.

Fig. 3 is a vertical transverse section on the line 3-3 of Fig. 1.

Fig. 4 is a vertical longitudinal section 50 on the line 4-4 of Fig. 2.

Fig. 5 is a vertical longitudinal section upon an enlarged scale on the line 5-5 of Fig. 2 through the controller side of the 55 controlling mechanism.

Fig. 6 is a vertical longitudinal section with parts broken away on the line 6-6 of Fig. 2, showing a portion of the connector plug side of the machine.

Fig. 7 is a plan view of a portion of the 60 controlling mechanism.

In the accompanying drawings in which it has been deemed unnecessary to illustrate the specific details of the controller mechanism and of the connector plug since these 65 may obviously assume different forms, 1 represents a mining machine frame at one side of which detachable current supply connections generally designated 2 are arranged and at whose other side the controller mechanism of the mining machine, generally designated 3, is disposed. The connector plug is of the push type and comprises in the illustrative form three power connections 4 and a ground connection 5 housed 70 within a longitudinally insertable and removable casing 6. The details of the circuit controlling mechanism, as mentioned above, are not disclosed, but operation of the motor of the mining machine 1 in opposite 75 directions is obtainable by opposite rotation of a squared operating shaft 7 which carries a cam plate 8 with which a pivoted locking element 9 cooperates under the tension of a spring 10. Shaft 7 is rotatable by a handle 80 12 which in its neutral position is disposed as shown in full lines in Fig. 2, but which may be moved in opposite directions 85 through angles of slightly less than 180 degrees to the dotted positions shown in 90 that figure.

The connector plug 6 is provided with a peripheral locking recess 15 with which the interlocking mechanism engages and is further provided with a radially extending recess 16 in which a manually releasable spring pressed plunger 17 slidably mounted in a chamber 18 upon an element secured to the machine frame 1 is engageable. The function of the locking plunger 17 is to 95 prevent blowing out of the connector plug 6 in the event of a short circuit or other condition causing an explosion within the machine casing at a time when the controller is in off position. Slidably but non-rotatably mounted upon the rectangular shaft 100 7 is a sleeve member 20 having peripheral teeth 20^a forming a rack. The member 20 is also provided in its periphery with a longitudinally extending recess 21 whose 105 110

opposite ends open into oppositely circumferentially extending peripheral recesses 22 and 23. A pin 24 formed at the end of a threaded bolt 24^a mounted on a part of the machine frame 1 extends into the groove made up of the portions 21, 22 and 23 and when the sleeve 20 is in the position shown in Fig. 7 precludes rotation of the shaft 7, but upon movement of the sleeve 20 longitudinally until the pin 24 is opposite the groove 22 or the groove 23 permits turning in one direction or the other of the shaft 7. Opposite longitudinal movement of the sleeve 20 is effected by a pinion 25 formed upon a transversely extending shaft 26 which has three flattened portions 27, 28 and 29 engageable by a leaf spring member 30 held by a bolt 31 to the machine frame. A handle 32 mounted upon the end of the shaft 26 is movable into upright, horizontal, and depending positions and respectively causes engagement of the surfaces 29, 28 and 27 by the leaf spring 30 when in such positions. The shaft 26 extends to a position beyond the central vertical longitudinal plane of the plug 6 and passes through the groove 15. The shaft 26 has a flattened portion 33 opposite groove 15 whereby with the parts in the position shown in Fig. 6 the plug may be freely inserted and removed, while the axis of the shaft as shown in Fig. 6 is so close to the periphery of the plug 6 that rotation of the shaft 26 to either position corresponding to the vertical dispositions of the handle 32 results in locking the plug against removal.

From the description which has been given the mode of operation of this device will be clearly apparent. Let it be assumed that the plug 6 is in position establishing electrical connections from the line to the machine and that the latch 17 is seated in the socket 16. The recess 15 then overlies the shaft 26 and the machine runner desiring to start the mining machine in one direction or the other will move the handle 32 from the position shown in Fig. 1 either clockwise or counterclockwise depending upon the direction of rotation of the motor desired. Rotation of the shaft 26 by movement of the handle 32 will bring either the surface 27 or the surface 29 opposite the leaf spring 30 so that the shaft will be held in the position to which it is moved and either rotation of the shaft will move the cutaway portion or flattened surface 33 into a vertical position and bring a cylindrical portion of the shaft 26 into the notch 15. Accordingly, it will be completely impossible even upon deliberate manual withdrawal of the latch pin 17 for the plug 6 to be removed while the controller is in "on" position, this being true irrespective of which direction the motor is running. The rotation of the shaft 26 operates through the pinion 25 to

move the rack sleeve 20 from the position shown in Fig. 7 longitudinally of the shaft 7 until the desired groove 22 or 23 comes opposite the pin 24. It will then be possible for the operator to move the handle 12 in the desired direction to effect controller operation. Obviously, if the handle 32 is moved to permit rotation of the handle 12 when the plug 6 is not in position, the plug cannot be inserted. Moreover, rotation of the handle 32 and shaft 26 is impossible with the plug partially inserted. It will therefore be apparent that the machine is well protected against willful or accidental manipulation of the parts in a manner to produce likelihood of explosions.

While I have in this application specifically described one embodiment which my invention may assume in practice, it will be understood that this invention may be modified and embodied in various other forms without departing from its spirit or the scope of the appended claims.

What I claim as new and desire to secure by Letters Patent is:

1. In an electric controlling mechanism, a shaft mounted only for rotation on a fixed axis and adapted on rotation in opposite directions from a given position to produce different circuits, and means including a member rotatable with said rotatable shaft and reciprocable longitudinally thereof and a stationary abutment member for controlling the direction in which said controller member may be moved.

2. In an electric controlling mechanism, a controller operating member, a connector plug, and means controlling the operation of said member and the removal of said plug including an independent manual operating element for said controlling means and a horizontal rotatable shaft adapted to interengage with the connector plug and provided with connections with the controller operating member so as to be operative in different positions to permit operation of said controller operating member and withdrawal of said plug.

3. In an electric controlling mechanism, a controller, manual means for operating the same, a removable connector plug through which power is conducted to said mechanism, and interlocking means cooperating with said plug and controller comprising a manually operable shaft, and means controlled thereby for preventing movement of said controller except in certain positions of said shaft, said shaft having a portion directly interlocking with said connector plug in said positions.

4. In an electric controlling mechanism, a controller, manual means for operating the same, a removable connector plug through which power is conducted to said mechanism, and interlocking means cooper-

- ating with said plug and controller comprising a manually operable shaft, and means controlled thereby for preventing movement of said controller except in certain positions 5 of said shaft, said shaft having a portion directly interlocking with said connector plug in said positions and means for yieldingly retaining said shaft in one of a plurality of positions.
- 10 5. In an electric controlling mechanism, a controller, manual means for operating the same including a shaft, means for controlling the power circuit leading to said controller, and interlocking mechanism co-operating with said means and controller comprising a member slidably and non-rotatively connected to said shaft, stationary means engageable with said member to prevent rotation of said shaft, manually operated means for effecting slidable movement to permit rotation of said shaft, and locking means for said circuit controlling means controlled by said manually operated means.
- 15 6. In an electric controlling mechanism, a rotatable shaft adapted on rotation in opposite directions from a given position to produce different circuits, a handle rigidly connected to said shaft for operating the same, and means including a member slidably and non-rotatively connected to said shaft, and means engageable with said member to make control of shaft rotation dependent on the longitudinal position of said member on said shaft.
- 20 35 7. In an electric controlling mechanism, a rotatable shaft adapted on rotation in opposite directions from a given position to produce different circuits, means comprising an element slidably and non-rotatively connected to said shaft and a stationary lug engageable with a groove in said member to make control of shaft rotation depend upon the longitudinal position of said mem-
- ber with reference to the shaft, and manually operated means for effecting slidable 45 movement of said member, and means controlling the power circuit leading to said controller, said manually operated means adapted also to control said circuit controlling means.
- 50 8. In an electric controlling mechanism, a controller, manual means for operating the same including a shaft, a removable connector plug, interlocking mechanism cooperating with said controller and plug comprising a member slidably and non-rotatively connected to said shaft, a handle rigidly connected to said shaft for operating the same, stationary means engageable with said member to prevent rotation of said shaft 60 except in certain longitudinal positions of said member, manually operated means for effecting slidable movement of said member, and locking means for said plug controlled by said manually operated means.
- 55 9. In an electric controlling mechanism, a controller, manual means for operating the same including a shaft, a removable connector plug, and interlocking mechanism co-operating with said plug and controller to 70 prevent removal of said plug while the controller is in on position, and also to prevent operation of said controller except when the locking means for the plug is effective, a member slidably and non-rotatively connected to said shaft, stationary means engageable with said member to prevent its rotation except in certain longitudinal positions, and means for effecting slidable movement of said member comprising a manually operat- 75 ed transverse shaft, a rack and pinion carried respectively by said member and shaft, and a locking device for said plug controlled by said transverse shaft.
- 80 In testimony whereof I affix my signature.
CHARLES W. WYMAN.
